UNITED STATES PATENT OFFICE.

JOHN E. DOBSON, OF NEW YORK, N. Y., ASSIGNOR TO E. W. BLISS COMPANY, OF BROOKLYN, NEW YORK, A CORPORATION OF WEST VIRGINIA.

DRAWING-PRESS.

1,212,192.

Specification of Letters Patent. Patented Jan. 16, 1917.

Application filed June 26, 1915. Serial No. 36,456.

To all whom it may concern:

Be it known that I, JOHN E. DOBSON, a citizen of the United States of America, residing in the borough of Manhattan, city, county, and State of New York, have invented certain new and useful Improvements in Drawing-Presses, of which the following is a specification.

My invention has relation to a drawing press and provides desirable improvements therein whereby variation in the parts during the dwell is practically completely overcome. Likewise, whereby the press may be run at a higher speed without injuring the blank and whereby torsional strain upon the press is obviated, the number of parts is reduced and a crank shaft is dispensed with.

These and other objects which will be set forth as the description proceeds are accomplished by the aid of my invention, which consists in providing direct driving connections from crank pins on each side of the press to the punch and in providing operating connections on each side of the press to a movable table from the same crank pins through interposed toggles whereby variation during the dwell of the table is obviated, and a simple, durable and efficient press is provided wherein the working parts are reduced to a minimum and torsional strain and stress is obviated, and an improved construction produced.

The most desirable form of my invention known to me is illustrated in the accompanying drawings.

In said drawings, Figure 1 is a side elevation of a press constructed according to my invention partly in section and partly broken. Fig. 2 is a front elevation thereof. Fig. 3 is a cross section on the line 3—3 Fig. 1. Fig. 4 is a diagram illustrating the toggle movements, and Fig. 5 is a diagram of the movements of the operating crank pin.

My invention is illustrated as applied to a press having side frames A, A¹ mounted upon a suitable base B and connected at their upper ends by a frame C. Between these side frames A, A¹ is located the stationary blank holder D, which is adjustably supported from the frame C by threaded

bolts d having nuts d¹, d² on respective sides of the blank holder. A movable punch-carrying-slide E is reciprocated in slides e and is attached to an overhead cross head F by adjustable connections including a threaded rod f having adjusting nuts f¹, f². A movable table G is reciprocated vertically and slides on ways provided by the side frames A, A¹.

The foregoing is a known type of press in connection with which I have illustrated my invention.

According to my invention crank pins H, H¹ located on rotary members X, X¹ are provided upon the respective sides of the machine and direct operating connections from these crank pins to the punch are obtained by links I, I¹ which are connected to the cross head F. From the same crank pins the table is driven and the operating means 70 for the table comprise first toggles which are operatively connected to the crank pins on each side, and third toggles which are connected to the table and operating connections between the toggles including second 75 toggles comprising a slide. In the manner of constructing my invention which is illustrated in the accompanying drawings the first toggles which are located on each side of the machine and are lettered J, J¹ (Figs. 80 1 and 3) are connected at one end to a rock shaft K which is rocked through links L, L¹ connected to each crank pin and to rocking arms M, M¹ on the rock shaft K. The table G is provided with vertically placed third 85 toggles which are preferably located at each corner thereof and are four in number and are lettered N, N¹, N². Table toggle which would be lettered N² is hidden from view.

The table or third toggles are connected to 90 rock shafts O, O¹ situated at the front and rear of the machine respectively. These rock shafts O, O¹ have rocking operating arms P, P¹ which are four in number, and of which two are seen in Fig. 1. Operating 95 arms P, P¹ and operating arms M, M¹ are fixed to their respective rock shafts. Links Q¹ connect the arms P¹ to the first toggles J and a slide R which is mounted to slide in the base B of the machine is pivotally con- 100

nected to the toggle J. The links Q, Q¹ and slide R in effect constitute second toggles and the slide likewise provides means whereby the table operating toggles at the front of the machine are operated, and for this purpose the links Q are pivotally mounted to the front of the said slide and to the arms P. The slide support provides an abutment for the links Q, Q¹. The rock shaft K is pivotally mounted in an extension B¹ of the base B which is strengthened by stay rods S, S¹ against a longitudinal strain during operation. Vertical stay rods T, T¹ connect the base B and the frame C and extend through each frame A, A¹.

It will be perceived from the foregoing drawings that the vertical movement of the punch as it hits the work, takes place during the time the crank pin is descending from its extreme uppermost position substantially 45°, but owing to the arc this is only one-eighth of the total vertical movement of the crank pin and accordingly the punch is moving very slowly when it hits the blank, and thereby I am enabled to run the press at a greatly increased speed. I have illustrated in Fig. 5 a diagram of the positions occupied by the crank pin during the performance of the various functions of its connected operating devices. The start is made at substantially zero which it will be perceived is about 45° short of the top or high point of the crank pin, and as stated the crank pin, when the punch hits the blank, is moving from its uppermost position to the point marked 85, and during this time the table is moved up to the work. At point 85° as seen in Fig. 1, toggles N, N¹, N², N³ are straight and the punch is then in the contact with the blank. The dwell of the table begins at 85° and continues to the point marked 235° occupying substantially 145°. During this time the punch is drawn down by the crank pins to perform its function. The travel of the crank pin during the dwell is, therefore, from 85° to 235°. These points are both on the same side of a diametrical line 1—1 (Fig. 5) which is drawn on the circle of rotation of the crank pin and is perpendicular to the mean longitudinal axis 2—2 of the connecting link. The arc traversed by the crank pin during the dwell of the table is less than half the circumference of its circle of rotation, and the longitudinal movement of the link is less than a radius of the crank pin's circle of rotation. By this means a minimum of movement is communicated from the crank pin to the arms M, M¹ during the period of dwell.

According to my invention I provide means whereby the amount of variation or movement of the table during dwell is reduced so that the same is practically nonexistent. In a press of a given size wherein

for instance the diameter of the path of rotation of the crank pin is 24 inches, the toggle vibration at U is approximately 10 inches or 5 inches each side of the center. This results in a longitudinal movement at the point V of 1½ inches giving a vibration of the second toggle of $\frac{3}{4}$ of an inch each side of the center. This is further reduced to a movement of the third series of toggles at the point W of eight one thousandths of an inch (.008) or four one thousandths (.004) at each side of the center and the vertical movement or variation therefore of the table during the period of dwell is reduced to three one millionths (.000,003) of an inch. It will be perceived therefore that this variation or movement of the table during dwell is so slight as to be incapable of detection by its effect upon the work or in any other way except by calculation and that the table is therefore practically immovable during the dwell.

The rotary main gears X, X¹ upon which the crank pins are mounted as illustrated, are on a shaft X² (Fig. 3) and are driven by pinions Y on shaft Y¹. Gear Y² on shaft Y¹ is driven from pinion Z on shaft Z¹ carrying gear Z² which meshes in pinion Z⁴ on the driving shaft Z⁵. Upon this driving shaft are pulleys Z⁶, a clutch Z⁷ and a balance wheel Z⁸. The shaft Z⁵ is mounted in posts Z⁹, Z¹⁰.

Although I have described with great particularity the construction of my invention it is obvious that the same is subject to change within the skill of the mechanic and that equivalent devices may be substituted for those illustrated, and the said devices may be differently arranged within the limits of the appended claims or applied to other types of presses. My invention is not concerned with the details of construction of the frame of the press or of the means of conveying motion to the crank pins although the same has been carefully described.

What I claim and desire to secure by Letters Patent is:—

1. In a drawing press, a movable table, and a pair of rotary members located on opposite sides of the press, a crank pin on each rotary member, a rock shaft, connections from each crank pin to said rock shaft, and duplicate trains of toggles between said rock shaft and said table.

2. In a drawing press, a movable table and a crank pin on each side of the press, and operating connections between said respective crank pins and said table comprising a rock shaft, a rocking connection thereto from each crank pin, and a plurality of trains of toggles between said rock shaft and said table.

3. In a drawing press, a crank pin on each side of the press, a movable table and connections thereto from said respective crank

pins comprising a rock shaft having a rocking connection to both of said crank pins, a toggle connected to said rock shaft, a toggle connected to the table and to a second rock shaft, and a rocking connection between the first toggle and the second rock shaft comprising a sliding abutment pivotally connected to the first toggle, and a toggle link pivotally connected to said slide, and a rocking arm on said second rock shaft and pivotally connected to said toggle link.

4. In a drawing press, a movable table and a crank pin on each side of said press for driving said table, and operating connections between each of said crank pins and said movable table comprising a rock shaft, a rocking connection from each crank pin thereto, a sliding abutment, two toggles connecting said sliding abutment and rock shaft, a second rock shaft, two toggles connecting the same and the table, rocking arms on said second rock shaft and two toggle links connecting the sliding abutment and said rocking arms.

25 5. In a drawing press having side frames, a movable table, main gears on the outside of each side of the frame, a crank pin on each gear and operating connections between each of said crank pins and said table comprising a rock shaft, a link connected to each of said crank pins for rocking said shaft, a slide and toggles operatively connected to said rock shaft and said slide, second rock shafts at the front and rear of the press, toggles between said second rock shafts and each corner of the table and rocking connections between said slide and said table toggles.

40 6. In a drawing press, a movable table and a crank pin on each side of said press for driving said table, and operating connections between each of said crank pins and said movable table comprising a rock shaft, a rocking connection from each crank pin thereto, a sliding abutment, two toggles connecting said sliding abutment and rock shaft, a pair of second rock shafts at the front and rear of the machine respectively, two toggles connected to each of said rock shafts and the table, two rocking arms on each of said second rock shafts, and four toggle links connecting said sliding abutment and said rocking arms.

45 7. In a drawing press, a movable punch and a movable table, a crank pin for driving both of said parts, a link directly connecting the crank pin and punch and a driving connection between the crank pin and table including a plurality of connected toggles, a link connecting the crank pin to the first toggle, a third toggle connected to the table, and a connection between said first and third toggles comprising a slide to which the first toggle is pivotally connected, 50 a second toggle arm pivoted to said slide,

and a rocking arm pivotally connected to said second toggle arm and operatively connected to the third toggle.

8. In a drawing press, a stationary blank holder, a movable punch, a movable table, a crank pin on each side of the press and direct driving connections from each of said crank pins to said punch and driving connections from each of said crank pins to said table.

75 9. In a drawing press, a movable punch, a crank pin on each side of the machine, a movable cross head carrying the punch and a link directly connecting each crank pin with said cross head, a movable table and driving connections thereto from said crank pins, comprising a rock shaft having a rocking connection to each of said crank pins, a toggle connected to said rock shaft, a toggle connected to the table and to a second rock shaft, and a rocking connection between the first toggle and the second rock shaft.

80 10. In a drawing press, a movable drawing member, a crosshead therefor, a crank for operating said drawing member, and a link directly connecting said crank and crosshead, said parts so connected that the drawing member contacts with the blank at not more than approximately 50° of the movement of said crank past its highest point whereby such contact takes place during the slower rate of travel toward the work of the drawing member.

85 100 11. In a drawing press, a movable punch, a crank pin for operating said punch and a driving connection between said parts, said parts so connected that the punch contacts with the blank during the early part of the movement of said crank pin past its highest point whereby such contact takes place during the slower period of travel toward the work of the punch, a movable table, a driving connection between the crank pin and table including a succession of operatively connected toggles connected to said table and to said crank pin, the parts so arranged and disposed that the dwell of the table occurs while the crank pin is traveling in its arc of rotation on one side of a line intersecting the center of rotation of the crank pin and perpendicular to the mean longitudinal axis of such connection, whereby the longitudinal movement of such connection is not greater than the radius of the circle of rotation of the crank pin and the table is substantially deprived of all variation relative to the work during the dwell.

115 120 12. In a drawing press, a movable table, a table operating crank pin, a driving connection between the parts, including a succession of operatively connected toggles, a connection at one end of said toggles to the table and at the other end to the crank pin, the parts so arranged and disposed that the

dwell of the table occurs while the crank pin is traveling in its arc of rotation on one side of a line intersecting the center of rotation of the crank pin and perpendicular to the mean longitudinal axis of such connection.

In witness whereof, I have hereunto

signed my name in the presence of two subscribing witnesses.

JOHN E. DOBSON.
